Attorney

UNITED STATES PATENT OFFICE.

GEORGE E. PELTON, OF GEORGETOWN, KENTUCKY.

TYPE-WRITER RIBBON.

1,182,929.

Specification of Letters Patent. Patented May 16, 1916.

Application filed February 14, 1916. Serial No. 78,165.

To all whom it may concern:

Be it known that I, GEORGE E. PELTON, a citizen of the United States, residing at Georgetown, in the county of Scott and State of Kentucky, have invented new and useful Improvements in Type-Writer Ribbons, of which the following is a specification.

This invention relates to improvements in typewriter ribbons.

It is the object of this invention to provide typewriter ribbons with a means of identification carried upon the ribbon which can not become obliterated by contact with the inked portion of the ribbon.

Typewriter ribbons are provided with some means of attaching one end of the ribbon to the spool upon which it is originally wound and the other end to the spool upon the machine and some are provided with a means, such as the eyelet, adjacent each end to coöperate with a part of the machine upon which it is used to automatically reverse the ribbon movement and while this invention may be applied to all forms of typewriter ribbons it is most advantageously applied to ribbons of the latter class.

While the preferred form is illustrated upon the accompanying sheet of drawing, yet it is to be understood that minor detail changes may be made without departing from the scope thereof.

Figure 1 is a top plan view of an embodiment of this invention with the identification means in the normal or covered position. Fig. 2 is a view in side elevation of the same. Fig. 3 is a view similar to Fig. 1 showing the identification means in the open position displaying the identification mark, symbols, letters or words.

While this invention may be applied to all forms or classes of inked typewriter ribbons it is illustrated in connection with a ribbon 1 having an eyelet 2 adjacent each end for coöperating with a part of the machine upon which it is used for automatically reversing the ribbon movement. In this form or class of ribbons, the eyelets are usually provided at a short distance from the ends of the ribbon and the ends are provided with hooks for attachment to the spools. In carrying out this invention, tabs 3, of the same width as the ribbon, are attached on one side of the ends of the ribbon 1 by the eyelets 2 and a hook 4 is secured preferably by an eyelet 5 adjacent the free ends of each tab for attach-

ment with the spool. An identification tab 6 of preferably less length and substantially twice the width of the first-mentioned tab 3 is secured at one end to the first-mentioned tab and ribbon end by the eyelet 2, preferably with the ribbon end between the tab, and to the free end of the first tab 3 by the eyelet 5, preferably carrying the hook 4.

The marks of identification of the ribbon are printed or otherwise indicated by letters, numbers, symbols, or the makers' name and address upon the outer face of the second tab 6, the top and bottom of which may be folded in upon the outer face to cover the identification means, as shown by Fig. 1, and preferably meet along the longitudinal center line, and the eyelet 2 may pass through the two tabs 3 and 6, ribbon, and folded in ends of the wider tab 6. The central portion of the body of the wider tab 6 is secured to the outer end of the first tab 3 by the eyelet 5.

During the original winding of the ribbon upon the spool and the continued winding and unwinding of the ribbon upon the spool during the ribbon movement when used upon the machine, a certain amount of the ink will be smeared or expressed upon the tabs 3 and 6 but the folded in portion of the identification tab will cover and protect the identification mark so that upon turning back the folded portion the ribbon may always be clearly identified.

This invention is not restricted to the particular form or manner of attaching the identification tab 6, as it is obvious that it is not necessary that the tab be folded in the particular manner shown because it could be folded centrally as well, nor is it necessary that the eyelet 2 pass through the folded-in end portion of the tab 6. The particular form or manner of attaching the end to the spool is immaterial as any of the means in general use could be substituted for the hook 4 without departing from the scope of this invention. This means of identifying inked typewriter ribbons and preventing the obliteration of such means not only can be applied to any form of inked ribbon for use in typewriters, adding machines, or other similar machines using inked ribbons, but it in no way interferes with the normal manner of attachment to the spool or with any automatic reverse of the ribbon movement and in this case it provides an extra length of inked ribbon

between the engagement means of the automatic reverse on each end which will not be wound up on the spool when the reverse takes place, and, furthermore, the eyelet 5 passing through the ribbon by also passing through the two tabs 3 and 6 is more firmly secured thereto and more rigidly resists the pull when it engages the reversing means. In other forms or classes of ribbons the 10 greater portion of inked ribbon may be used as the ends may be unwound the length of the tab from the spool.

What I claim is:—

1. In a typewriter ribbon, an identification tab secured to the end thereof, a spool attaching means secured to the free end of the tab and said tab folded over upon itself between the ribbon and spool attaching securing means, whereby the identification 15 marks are covered and protected by the folded parts of the tab.

2. In a typewriter ribbon, a tab secured to the end thereof, an identification tab secured to the end of the ribbon and first- 25 named tab having a portion adapted to be folded over and upon itself to cover and protect identification marks, and a spool at-

taching means secured to the free ends of the tabs.

3. An identification means for typewriter 30 ribbons comprising a tab of substantially a greater width than the ribbon adapted to be folded over and upon itself to cover and protect the identification marks, means for securing one end of the tab to the ribbon 35 end, and means for attaching the free end of the tab to the typewriter spool.

4. As an article of manufacture, means for identifying typewriter ribbons comprising a tab of substantially the same width as 40 the typewriter ribbon and an identification tab of substantially a greater width than the typewriter ribbon folded over and upon itself to cover and protect the identification marks, means to secure the corresponding 45 ends of the tabs to each other and the end of the ribbon, and means to attach the free end of the tabs to the ribbon spool, said identification tab adapted to be unfolded to display the identification mark.

GEORGE E. PELTON.
